UNITED STATES PATENT OFFICE

2,533,761

GARMENT FINISHING APPARATUS

Robert W. Brenner, Foster's, and John E. Petre,
Cincinnati, Ohio, assignors to The American
Laundry Machinery Company, Cincinnati,
Ohio, a corporation of Ohio

Application March 20, 1947, Serial No. 735,878

15 Claims. (Cl. 223—70)

1

This invention relates to garment finishing apparatus of that type in which the garment, such as a man's or a woman's coat, jacket or overcoat or other garment, is dressed upon a pervious but rigid form to which it is shaped while passing steam or air through it during the usual garment finishing treatment or process.

One object of the invention is to generally simplify and improve such apparatus by combining in one machine a tilting and rotatable divided form by means of which steam or air flow may be confined to one half of the garment with an efficient steamer and air heater, and unusually simple and convenient means for controlling and directing the flow of air or steam.

Another object is to provide such apparatus in which the controlling devices, which here are foot pedals, are all brought into close neighboring relation convenient for use by the operator at the control station without changing her position.

Another object is to shorten and straighten the air and steam passages, thus decreasing overall bulk and securing increased efficiency.

Still another object is to improve the supports or mounting for the form, thus holding it in place more solidly and firmly and avoiding any chance of its escape from the base, but yet enabling it to be freely, smoothly and easily adjusted to any desired position.

Another object is to simplify and improve the damper mechanism, and the operating means therefor, which controls the direction of air flow.

Another object is to provide simple, efficient and easily operated latches for certain of the control devices, enabling them to be easily operated by the foot, so that the operator's hands may be employed entirely upon the garment itself and the form upon which it is supported.

A further object is to provide an improved apparatus of this kind capable of use interchangeably with various types or styles of form, such as a form for men's overcoats, one for women's jackets, a dress form, or any other style.

Further objects of the invention in part are obvious and in part will appear more in detail hereinafter.

In the drawings, which represent one suitable embodiment of the invention,

Fig. 1 is a side elevation, partly broken out and in section, part of the form being shown in dot and dash lines, and the damper operating parts being shown in blocking or by-pass position;

Figs. 2 and 3 are generally similar views, on a smaller scale, showing the same operating parts, respectively, in air suction and air pressure positions;

2

Fig. 4 is a plan view, partly broken out and in section, the form being omitted;

Figs. 5, 6 and 7 are simplified, broken out plan views, showing various positions of the air flow controlling dampers and linkage, corresponding respectively to Figs. 2, 3, and 1;

Fig. 8 is a front elevation, partly broken out and in section, showing the form in erect or upright position;

Fig. 9 is a fragmentary side elevation, from the right in Fig. 8;

Fig. 10 is a detail front elevation of the form latching mechanism, with the form in tilted position;

Fig. 11 is a detail sectional elevation, on the line 11—11, Fig. 1, showing the form registering devices;

Fig. 12 is a detail sectional elevation on the line 12—12, Fig. 4;

Fig. 13 is a detail sectional plan view, on the line 13—13, Fig. 12, certain covering parts being removed, and with the tilting member in an upright position;

Fig. 14 is a detail sectional plan view on the line 14—14, Fig. 12; and

Fig. 15 is a fragmentary plan view of a portion of the form tilting and sealing devices, with gaskets omitted to clarify the illustration.

Referring first to Fig. 12, the garment finishing apparatus shown in the drawings includes a circular base 10 supporting a floor 11 and drum-like housing 12 which enclose an air heating chamber 13, within which is located the air heating and steam supplying pot or member, marked 14, bolted to the floor and later described in detail. Rigid lateral parallel arms 15 on the base support an electric or other form of motor or power unit 16 coupled to drive a suitable fan or blower 17. Steam pot 14 in turn supports the garment receiving form, marked generally 18, which may be of any desired shape or form, depending upon the style or character of the particular garments to be finished. One form may be used, for example for men's overcoats, and another, interchangeable with the first, for ladies' jackets, another for ladies' dresses, and so on, as will be readily understood.

The heater and steamer

50 The steam pot 14, in general, is like that shown, described and claimed in a prior patent for Garment Finishing Apparatus, No. 2,421,203, granted May 27, 1947, to George W. Johnson, to which reference may be had if desirable or necessary, so that brief description thereof will suffice. It includes outer and inner walls 19, 20, the former

having heat radiating fins or ribs 22, said walls enclosing a heating chamber 21 through which steam is circulated from the supply pipe 23 to the drain or exhaust pipe 24 (Figs. 12 and 8). From the chamber 21 steam may be caused to flow by way of pipe 25 and whistle valve 26 to the discharge pipe 27, which directs the steam against the hot bottom of the inner pail or wall member 20 (Fig. 12), thus preventing condensation and consequent water spotting of the garment. Valve 26 (spring biased to valve closed position) has the usual operating lever 28 connected by link 29 to treadle 30, by which it may be opened to any desired amount, while a multiple notched latch lever 31, foot operated and biased by spring 32, releasably holds the treadle 30 in any position to which it may be adjusted. Steam discharged into the pail member 20 rises, or is carried by the air stream, into the hollow pervious form 18, through the pervious wall of which it is distributed to and upon the garment dressed thereon, for the removal of wrinkles and otherwise to assist in shaping of the garment, as is usual.

The outer surface of the outer wall 19 of the steam pot, with its ribs 22, continually supplies heat to the air current flowing through chamber 13, so that, at any time, hot air may be likewise distributed over and passed through the garment.

The air flow system

Upon a collar 33 at the inlet end of the fan, and upon the base extensions 15, is supported a conduit member 34, communicating openly, at its inner end, with the air chamber 13 through an opening in the housing or casing 12. A center wall 35 divides the space within the conduit into two channels 36, 37, each opening into the air chamber 13, as before stated, the channel 36 communicating with the air inlet to the fan and the channel 37 with its outlet. (Figs. 1 to 7.) Each channel has a side opening 38 to atmosphere, shielded by a coarse screen 39, that to channel 36 being provided with a slidably, manually adjustable cover 40, Fig. 1, by which it may be partially closed or opened to any amount to regulate the quantity of air flow, and that to channel 37 being provided with an external deflector 41, Fig. 4, to deflect outflowing air away from the operator.

Airflow through channels 36, 37, is controlled by two dampers 42, 43, one opposite each opening 38.

Damper 42 is on a shaft 44 having an arm 45 connected by link 46 to one arm 47 of a pivoted bell crank lever having a foot treadle 48. By depressing this treadle, damper 42 may be moved from the position shown in Fig. 6 to that shown in Fig. 5.

Damper 43 is on a shaft 49 having an arm 50 connected by link 51 to one arm 52 of a two armed lever mounted to turn on but not with shaft 44, the other arm 53 of said lever being connected by link 54 to one arm 55 of a lever having a second arm 56 connected by link 57 to one arm 58 of a bell crank lever having a foot treadle 59. By depressing foot treadle 59, damper 43 may be moved from the position shown in Fig. 5 to that shown in Fig. 6.

A third treadle 60 has its rear arm 61 provided with a cross pin 62, the two ends of which, respectively, lie beneath treadle levers 45, 59. By depressing treadle 60, either or both of treadles 43, 59 (whichever may be down) may be elevated to return the damper which it operates to its other position.

Fig. 7 illustrates the parts in their normal blocking or by pass position, resulting from depression of treadle 60. No air flows to or from the garment form, but only from one opening 38 through the fan to the other. Steam, however, may be supplied to the form and garment by depressing treadle 30.

In Fig. 5, the right hand suction or vacuum treadle 43 has been depressed, moving damper 42 to close the inlet opening 38. Suction is effective in the form and air is drawn in through the garment and discharged through the outlet opening 38.

In Fig. 6, the left hand blower or air supply treadle 59 has been depressed, closing damper 43 over the outlet opening 38. Air from atmosphere enters channel 36 and is forced through channel 37 by the fan, is heated in chamber 13 and then is forced outwardly through the garment.

Thus the operator, by appropriate operation of the several treadles, is enabled to either steam the garment without or with hot air, or subject it to inward flow of atmospheric air alone or outward flow of heated air alone, at will.

The tilting and turning form

As before stated, the form is carried upon and by the steam pot. This firmly supports two brackets 63, each carrying one of a pair of opposite alined pins or trunnions 64 on which is journalled a cylindrical or drum like form supporting member 65 having a central hub 66 and four radiating walls or spokes 67. Half only of one end opening 68 of the cylinder is closed by a cross wall 69. In the hub 66 is mounted a bushing or bearing member 70 having a top flange 71 seating on hub 66, and into which bushing depends a shaft or post 72 of the form 18. This enables the form to be rotated about a vertical axis upon its support or to be taken out and replaced by another form with a like depending post but shaped to receive different garments.

The space within the form is divided by a cross wall 73 into two separate chambers 74, 74a, said wall at its upper end supporting the neck block or form 75 and suitable shoulder supporting arms attached thereto (not shown). Wall 73, of course, is imperforate, being made of sheet metal, while the garment supporting member 76 of the form, on which the garment is dressed, is of porous material, comprising a relatively rigid mesh structure covered by a closely fitting, non-expandable cover.

Wall 73 is rigidly mounted upon a base including an outer collar or ring 77 and a hub 78 connected by radial spokes 79, two of which are in the same plane as wall 73. Shaft 72 is secured to the hub 78, while the skirt of form member 76 is fastened to ring 77 by a sleeve 79a. The lower edges of spokes 79 lie close to the upper edges of spokes 67 and ring 77 has a flange 80 closely encircling the cylindrical wall of member 65 (Fig. 12).

Around the front of the apparatus, the form support is provided with a depending crescent shaped sealing flange or shell 81, of spheroidal form. Its outer surface is polished and smooth and is in contact with the edge of a felt sealing gasket 82 fixed to the casing 12. A stop 83 on shell 81 engages the upper edge of the casing to prevent the form from tipping forwardly, or toward the operator, beyond the vertical. This sealed joint prevents escape of air or steam from the heating chamber around the front half of the machine.

The rear half of the device is similarly sealed. This time, however, the spheroidal shell member 84 is fixed to the casing, while the gasket 85 is mounted on and moves with the tilting form along the inner surface of the shell, thus sealing the joint around the rear half of the machine.

Cover plates 86, 87, one on the support 65 at the front, and the other on the casing at the back cover the sealing parts, protect garments from oil, grease, dirt, etc., and improve the appearance.

At the front (Fig. 12), support 65 is provided with a depending arm 88 on which hangs a latch bar 89 having a lateral arm 90 from which a tension spring 91 extends to a lug 92 on the machine base, thus biasing bar 89 to swing to the right (Fig. 8). This spring also is strong enough to hold the garment form firmly in upright or vertical position.

On the front of the steam pot 14 (Figs. 10 and 12), is a rectangular lug or boss 93, on which is pivoted a bellcrank tripping member 94, one arm of which is connected by link 95 to a treadle lever 96 pivoted on the base. The other arm is provided with a pin 97 lying opposite the edge of lever 89 and cooperating with a V-shaped notch or recess 98 therein. Lever 89 also has a rectangular notch 99 in its same edge.

Fig. 8 shows the parts in normal, upright position, in which they are yieldingly held by spring 91. When the operator tilts the form rearwardly (by hand pressure applied to it), latch bar 89 is carried upwardly. As it rises its sloping edge 100 engages pin 97, rocking lever 94 clockwise (Fig. 8) and lifting treadle 96. When the limit of tilt is reached, the rectangular notch 99 comes opposite lug 93 and the bar snaps over to engage the lug in the notch, thus firmly, but releasably, locking the form in tilted position. Now, whenever treadle 96 is depressed, the pin 97 on bell crank lever 94 is swung to the left, bearing against the latch bar, and more particularly against the upper edge of the V-shaped notch 98 therein. The effect is to slightly lift the latch bar and reduce friction and wear at the rectangular notch, so that bar 89 is easily swung to the left, freeing the lock and permitting the form to move to upright vertical position under tension of spring 91.

As before stated, form 18 is rotatable on its support about a vertical axis. Means is provided to definitely locate or register the form in either of two positions, in each of which the cross wall 73 extends transversely and is co-planar with the transverse cross ribs 67. The means shown therefore in Fig. 11 includes two cups 101, each containing a latching dog or ball 102 pressed upwardly by a spring 103 against the flange 80 of the form base member and adapted to partially enter one of two oppositely disposed recesses 104 therein.

This arrangement enables the form to be turned so that either its front (at the left in Fig. 9) or its back faces the operator, enabling her to work on any part of the garment without changing her position. In either position of the form, air flow from the heating chamber to and through the form, or in the reverse direction, is permitted only through that half of the form (chamber 74 or 74a) nearest to the operator, flow through the other half being blocked by the cross wall or floor 69 of support 65. All joints between relatively movable parts are either sealed, as by gaskets 82, 85 or are very close, as between flange 80 and the cylindrical wall of member 65, so that no hot air or steam escapes, except through the form and garment or from the fan outlet at deflector 41.

By depression of the appropriate treadle 48, 59 or 60 either steam alone, or steam and hot air, may be applied to the garment, or suction may be caused to draw air inwardly through it. By tilting the form the garment may be more closely fitted or applied to it.

The air vacuum system is very simple, with short straight passages, and with reduced overall bulk by location of the steam pot beneath the form. The treadle control mechanism is also very simple and easy to operate. Also, while the form is readily removed for replacement or repair, it is stable in position, with no chance of accidental escape from its support. Again, all latching and tripping mechanism is enclosed and protected and the machine has a pleasing external appearance.

It should also be noted that the form supporting member serves four distinct purposes, to wit, to rotatably support the form, to provide pivotal mounting therefore about a transverse horizontal axis, as an air seal, and to close off the back compartment of the form against air flow.

Other advantages of the invention will be apparent to those skilled in the art.

What we claim is:

1. Garment finishing apparatus of the character described, comprising a hollow, chambered base, a pervious hollow garment form mounted upon said base with the space therein open to the chamber of the base, an air heater in the base chamber, a blower at one side of the base, short, straight conduits connecting the inlet and outlet of the blower to the base chamber, each provided with an opening to atmosphere, and a damper for each opening.

2. Garment finishing apparatus of the character described, comprising a hollow, chambered base, a pervious hollow garment form mounted upon said base with the space therein open to the chamber of the base, an air heater in the base chamber, a blower at one side of the base, short, straight conduits connecting the inlet and outlet of the blower to the base chamber, each provided with an opening to atmosphere, and a damper for each opening mounted within its conduit and movable from a first position closing its opening to a second position closing its conduit from the base chamber.

3. Garment finishing apparatus of the character described, comprising a hollow, chambered base, a pervious hollow garment form mounted upon said base with the space therein open to the chamber of the base, an air heater in the base chamber, a blower at one side of the base, short, straight conduits connecting the inlet and outlet of the blower to the base chamber, each provided with an opening to atmosphere, a damper for each opening mounted within its conduit and movable from a first position closing its opening to a second position closing its conduit from the base chamber, and means for independently actuating the two dampers.

4. Garment finishing apparatus of the character described, comprising a hollow, chambered base, a pervious hollow garment form mounted upon said base with the space therein open to the chamber of the base, an air heater in the base chamber, a blower at one side of the base, short, straight conduits connecting the inlet and outlet of the blower to the base chamber, each provided with an opening to atmosphere, a damper for each opening mounted within its conduit and movable from a first position closing its opening to a second position closing its conduit

from the base chamber, and two foot treadles, one connected to each damper and adapted when depressed to move it to its first position.

5. Garment finishing apparatus of the character described, comprising a hollow, chambered base, a pervious hollow garment form mounted upon said base with the space therein open to the chamber of the base, an air heater in the base chamber, a blower at one side of the base, short, straight conduits connecting the inlet and outlet of the blower to the base chamber, each provided with an opening to atmosphere, a damper for each opening mounted within its conduit and movable from a first position closing its opening to a second position closing its conduit from the base chamber, two foot treadles, one connected to each damper and adapted when depressed to move it to its first position, and a third foot treadle operatively associated with the said two foot treadles and adapted when depressed to elevate either or both thereof and thereby return their dampers to the second position.

6. Garment finishing apparatus of the character described comprising a hollow, chambered casing having a circular top opening, means for causing the flow of air through said chamber and opening, a hollow pervious garment form provided with a wheel-like base having a rim, spokes and a hub, and a shaft depending from said hub, and a form supporting member pivotally mounted upon the base to turn upon a horizontal axis and extending across its top opening and having a cylindrical rim, spokes and hub, the last named hub being provided with a bearing bushing to receive said shaft and upon which the form base hub is supported.

7. Garment finishing apparatus of the character described comprising a hollow, chambered base having a circular top opening, means for causing the flow of air through said opening and chamber, a hollow pervious garment form provided with a wheel-like base having a rim, spokes and a hub, and a shaft depending from said hub, and a form supporting member mounted upon the base and extending across its top opening and having a cylindrical rim, spokes and a hub, said hub being provided with a bearing bushing to receive said shaft and upon which the form base hub is supported, and a semi circular horizontal floor closing the space between certain of the spokes of the supporting member and thus shutting off air flow through such space.

8. Garment finishing apparatus of the character described comprising a hollow, chambered base having a circular top opening, means for causing the flow of air through said opening and chamber, a hollow pervious garment form provided with a wheel-like base having a rim, spokes and a hub, and a shaft depending from said hub, and a form supporting member mounted upon the base and extending across its top opening and having a cylindrical rim, spokes and a hub, said last named hub being provided with a bearing bushing to receive said shaft and upon which the form base hub is supported, said supporting member being pivoted on the base, and a spheroidal sealing shell of crescent form and a cooperating gasket, one on the base and the other on the supporting member, for preventing air leak between them.

9. Garment finishing apparatus of the character described comprising a hollow, chambered base having a circular top opening, means for causing the flow of air through said opening and chamber, a hollow pervious garment form pro-

vided with a wheel-like base having a rim, spokes and a hub, and a shaft depending from said hub, and a form supporting member mounted upon the base and extending across its top opening and having a cylindrical rim, spokes and a hub, said last named hub being provided with a bearing bushing to receive said shaft and upon which the form base hub is supported, said supporting member being pivoted upon the base upon an axis diametrical to and across said opening, and spheroidal sealing shells of generally crescent form, one on each side of the pivotal axis, for sealing the joint between the base and supporting member in various positions of the latter.

10. Garment finishing apparatus of the character described comprising a hollow, chambered base having a circular top opening, means for causing the flow of air through said opening and chamber, a hollow pervious garment form provided with a wheel-like base having a rim, spokes and a hub, and a shaft depending from said hub, and a form supporting member mounted upon the base and extending across its top opening and having a cylindrical rim, spokes and a hub, said last named hub being provided with a bearing bushing to receive said shaft and upon which the form base hub is supported, said supporting member being pivoted upon the base upon an axis diametrical to and across said opening, and spheroidal sealing shells of generally crescent form, one on each side of the pivotal axis, for sealing the joint between the base and supporting member in various positions of the latter, one of said shells being attached to the base and the other to the supporting member.

11. Garment finishing apparatus of the character described comprising a hollow, chambered base, having a circular top opening, means for causing the flow of air through said opening and chamber, a hollow pervious garment form provided with a wheel-like base having a rim, spokes and a hub, and a shaft depending from said hub, and a form supporting member mounted upon the base and extending across its top opening and having a cylindrical rim, spokes and a hub, said last named hub being provided with a bearing bushing to receive said shaft and upon which the form base hub is supported, said supporting member being pivoted upon the base upon an axis diametrical to and across said opening, and spheroidal sealing shells of generally crescent form, one on each side of the pivotal axis, for sealing the joint between the base and supporting member in various positions of the latter, one of said shells being attached to the base and the other to the supporting member, and a gasket for each shell.

12. Garment finishing apparatus, of the character described, comprising a hollow chambered base having a circular top opening, a supporting member pivotally mounted upon said base upon an axis diametrical to and across said opening, a hollow garment form mounted upon said supporting member, a latch bar depending from and mounted to swing upon said member and having a side notch, a fixed lug on the base cooperating with said notch, and a spring connected to said bar and biasing it toward said lug to interengage the two, and a spheroidal sealing shell of generally crescent shape mounted upon the supporting member and closing any gap between it and the base and also covering and concealing the latch bar mechanism.

13. Garment finishing apparatus of the character described, comprising a hollow, chambered

base having a circular top opening, a steam pot and air heater within the base below said opening, and a hollow garment supporting form pivotally mounted upon said steam pot upon a horizontal axis diametrical to and across said opening.

14. Garment finishing apparatus of the character described, comprising a hollow, chambered base having a circular top opening, a steam pot and air heater within the base below said opening, a hollow garment supporting form pivotally mounted upon said steam pot upon a horizontal axis diametrical to and across said opening, and a spheroidal sealing shell of generally crescent shape for closing the gap between the base and form in various positions of the latter.

15. Garment finishing apparatus of the character described, comprising a hollow, chambered base having a circular top opening, a steam pot and air heater within the base below said opening, and a hollow garment supporting form pivotally mounted upon said steam pot upon a horizontal axis diametrical to and across said opening, and two spheroidal sealing shells of generally crescent shape, one on the base and the other connected to the form for closing any gap between base and form in various positions of the latter.

totally mounted upon said steam pot upon a horizontal axis diametrical to and across said opening, and two spheroidal sealing shells of generally crescent shape, one on the base and the other connected to the form for closing any gap between base and form in various positions of the latter.
